CLAIM

The ornamental design for a bottle cap for edible oil, substantially as shown and described.

DESCRIPTION

FIG. 1 is a front perspective view of a bottle cap for edible oil in an open position showing my new design; FIG. 2 is a front perspective view thereof in the closed position;

FIG. 3 is a top plan view thereof;

FIG. 4 is a bottom view thereof;

FIG. 5 is a front elevational view thereof, the rear elevation of which being a mirror image thereof;

FIG. 6 is a left side elevational view thereof; and

FIG. 7 is a right side elevational view thereof.
